FULL-FASHIONED KNITTING MACHINE

Montroy Jeffrey, Philadelphia, Pa., assignor to
Textile Machine Works, Wyomissing, Pa., a cor-
poration of Pennsylvania

Application July 10, 1946, Serial No. 682,651

24 Claims. (Cl. 66—89)

1

The present invention relates to fashioning mechanism for full-fashioned knitting machines and more particularly to fashioning mechanism for use in single unit machines adapted to effect certain improvements in the heel portion of full-fashioned stockings.

The fashioning heads, so-called narrowing heads, of full-fashioned knitting machines, include two threaded spindles, one for positioning the stops for the yarn carrier rods and one for moving the combs on which the fashioning points are fixed. Many variations of fashioning mechanism for full-fashioned knitting machines have been developed. Some of those proposed for use in single unit stockings, however, are complex and contain a large number of parts due to the fact that certain commercially desirable forms of heel construction in single unit stockings require a number of different routines of the fashioning spindles. The more common form of fashioning operation involves a rotative movement of said spindles in the narrowing direction sufficient to move the end stops and points both a two needle distance that is, twice the distance between next adjacent needles, while other forms of fashioning operations adopted for narrowing as well as for widening a considerable number of forms of heels for single unit stockings involve a rotative movement of the comb spindle sufficient to move the points a single needle distance only but a rotative movement of the end stop spindle in each direction sufficient to move the end stops a two needle distance at alternate movements of the comb spindle.

The reason the end stops are moved a greater distance than the points in single needle fashioning operations is that the yarn carriers, of ordinary construction, may only be stopped above dividers which are spaced in alternate relation with the sinkers and are therefore spaced a distance equal to twice the distance between the adjacent needles. Therefore, while it is desirable to move the points a one needle distance either in the narrowing or widening direction, the end stops for the yarn carriers must be moved a distance of two needles to always stop the yarn carriers over a divider.

Also, a feature incorporated in full-fashioned knitting machines is the auxiliary or pull-back pawl for the point comb spindle which normally moves the comb spindle idly a one needle distance immediately following certain of the fashioning operations of the points. Means is also provided to control the time and length of op-

2

eration of the pull-back pawl according to the fashioning pattern desired.

It is accordingly an object of the present invention to provide a fashioning mechanism for full-fashioned knitting machines adapted to move the spindles in a wide variety of fashioning routines and which shall be simple in construction and operation.

Another object of the invention is to provide a simple, economical and convenient means for controlling the operation of the end stop and point comb spindles to move through a two needle distance at each fashioning operation or to move the point comb spindle through a single needle distance either in the widening or narrowing direction and the end stop spindle only in alternate movements of the point comb spindle.

A further object of the invention is to provide means for operating the end stop and point comb spindles for fashioning the fabric in one or two needle steps and for idly moving the point comb spindle immediately following certain of the single needle steps.

A still further object of the invention is to provide means for operating the end stop and point comb spindles in narrowing and widening directions to fashion the fabric and including means for idly moving the point comb spindle during alternate fashioning operations.

With these and other objects in view, which will become apparent from the following detailed description of the illustrative embodiments of the novel fashioning mechanisms shown in the accompanying drawings, the invention resides in the novel elements, features of construction and arrangements of parts in cooperative relationship as hereinafter more particularly pointed out in the claims.

40 In the drawings:

Figure 1 is a diagrammatic illustration of a flat knitted blank for a novel form of single unit full-fashioned stocking which may be made by mechanism within the present invention;

45 Fig. 2 is a detailed view on an enlarged scale of one of the heel portions of the blank shown in Fig. 1;

Fig. 3 is an end elevational view of a full-fashioned knitting machine having a form of fashioning or so-called narrowing head within the invention, parts being omitted for purposes of illustration;

Fig. 4 is an enlarged view of a portion of the mechanism shown in Fig. 3, with the parts shown in different relative positions;

Fig. 5 is an elevational view of the mechanism shown in Fig. 4 as seen from the right of said figure;

Fig. 6 is an elevational view of the mechanism shown in Fig. 4 as seen from the left of said figure;

Fig. 7 is a detailed view of a portion of the mechanism shown in Fig. 4 but with the parts in different positions relative to Fig. 4;

Fig. 8 is a view similar to a portion of Fig. 7 but with the parts shown in different relative positions;

Fig. 9 is a view similar to Fig. 8 but showing the parts in different relative positions;

Fig. 10 is a detailed plan view partially in section of certain of the parts shown in Fig. 7 as viewed in the direction of the arrows 10—10.

Fig. 11 is a detailed plan view similar to Fig. 10 as viewed in the direction of the arrows 11—11 of Fig. 9;

Fig. 12 is a detailed view of certain of the mechanism shown in Fig. 4, showing the narrowing pawls for the end stop and comb spindles and means for controlling them during two needle and single needle narrowing operations, parts being omitted and parts being shown in section for purposes of illustration;

Fig. 13 is a view similar to Fig. 12 but showing the parts in different relative positions;

Fig. 14 is a front elevational view of a portion of the mechanism shown in Fig. 3 showing a control means for the spindle operating pawls;

Fig. 14A is a detail view showing a portion of the machine adjoining on the right the portion shown in Fig. 14.

Fig. 15 is a detailed view partially in section taken along the line 15—15 of Fig. 16;

Fig. 16 is a plan view of parts as viewed in the direction of the arrows 16—16 in Fig. 14, certain parts being omitted;

Fig. 17 is a sectional detailed view taken substantially on the line 17—17 of Fig. 16, looking in the direction of the arrows;

Fig. 18 is a view similar to Fig. 1 of a further form of full-fashioned stocking blank which may be produced by mechanism within the invention;

Fig. 19 is a detailed view on a much enlarged scale of a heel part shown in Fig. 18;

Fig. 20 is a detailed view similar to a portion of Fig. 19 showing a different arrangement of lace openings and fashioning marks in the lower portion of a heel part from that shown in Figs. 18 and 19 and as made by mechanism within the invention;

Fig. 21 is a view similar to Fig. 4 but showing a modified form of mechanism from that shown in Figs. 3 to 17, inclusive, for forming the heel structure shown in Figs. 18 and 19;

Fig. 22 is a detailed view of a portion of the mechanism shown in Fig. 21, taken as looking from the right of Fig. 21, parts being omitted for purposes of illustration;

Fig. 23 is an elevational detailed view of a portion of Fig. 21, the parts being shown in different relative positions from those in Fig. 21, parts also being omitted for purposes of illustration;

Fig. 24 is a sectional detailed view taken substantially on the line 24—24 of Fig. 23 looking in the direction of the arrows; and

Figs. 25, 26, 27, 28 and 29 are elevational detailed views looking from the left of Fig. 23 of a portion of a control means and showing the parts in positions assumed in different parts of a control cycle.

In the drawings and description, only the means and method necessary to a complete un-

derstanding of the invention have been specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

2. Three Catalogs entitled—The “Reading” Full-Fashioned Knitting Machine Parts Catalog—published and copyrighted by the Textile Machine Works, in 1929, 1935 and 1940, respectively.

3. Booklet entitled—The “Reading” High-Production Full-Fashioned Knitting Machine—which form a supplement to the above noted 1940 Parts Catalog of the Textile Machine Works, 20 and which Booklet is a publication of the Textile Machine Works, and was copyrighted by the latter in 1940.

4. Pamphlet entitled—Knitting Machine Lectures—published by the Wyomissing Polytechnic Institute, Wyomissing, Pennsylvania, in 1935.

The full-fashioned knitting machine and particularly the fashioning apparatus shown in Figs. 3 to 17, inclusive, is for forming stocking blanks of the type shown in Fig. 1, while the fashioning apparatus shown in Figs. 21 to 29, inclusive, is to be employed principally in making stocking blanks of the type shown in Fig. 18, both apparatus, however, being adaptable to make other forms of full-fashioned stocking blanks.

35 In both forms of apparatus within the invention, there are two threaded spindles in a fashioning head, one for moving the end stops and one for moving the point combs, and means whereby said spindles may be turned in either direction as desired. The end stop spindle is moved always in two needle steps, and the comb spindle in either two needle or single needle steps when loops are transferred in the narrowing direction, in single needle steps only when loops are transferred in the widening direction and in two needle steps only when making idle movements

40 in the widening direction. Further, the two needle idle steps of the comb spindle may be prevented when desired after certain of or all narrowing operations and certain widening operations or may be permitted only during narrowing operations and prevented during widening by the hereinafter described control means for said comb spindle. Also, a simple and convenient manually controlled means is provided whereby the narrowing pawl for the end stop spindle may be thrown out of action at alternate loop transferring movements of the comb spindle whether or not the comb spindle makes idle movements

45 in the loop transferring cycles. Moreover, means are included for throwing out of action the widening pawl for the end stop spindle at alternate loop transferring movements of the comb spindle.

50 Referring more particularly to Figs. 1 and 2, 30 is a flat single unit full-fashioned blank for a stocking assumed to have been knitted on a machine equipped with the mechanism shown in Figs. 3 to 17, inclusive. Blank 30 comprises a top part formed of a welt 31, preferably of the two ply type, followed by an upper leg portion having narrowing or fashion marks 32. Below the narrowings 32 is a leg part 34 having parallel selvages and part 34 is followed in turn by a lower 55 leg part having lines of narrowing or fashion

marks 36. Below the fashion marks 36 is an ankle part 38 having parallel selvages below which is another part having parallel selvages and containing the high-heel reinforcements 40. The reinforced area extends from the high heels along both sides of the blank to the toe, the line 41 indicating the inner edge of the reinforcement. Immediately below the high heel parts are heel parts 42, which also are of reinforced fabric, and immediately following these latter are parallel sided parts 44. Following parts 44 are parts having gusset narrowings 46. Following the narrowings 46 is a part 48 having parallel selvages and the reinforced edges of which form the sole, while following the part 48 is one having lines of toe narrowings 50 extending substantially to the lower end of the stocking at the tip of the toe, which is shown as having a group of ravel courses 52 extending therefrom and provided to facilitate looping the course at the tip of the toe.

The structure of the heel parts 42 is best understood from Fig. 2. Parts 42 are formed by widening the fabric by means of the fashioning points and then narrowing the fabric after sufficient width of fabric has been attained. Widening operations are performed in parts 42 in every other course and each widening operation of the points steps out the edge loops a single needle distance. Lines of lace openings 56 are formed along the inner edge of the widened heel parts 42. As mechanical considerations require that the end stop spindles move two needles each time they are operated while comb spindles move only one needle in widening, the selvages are built out at the desired rate of one needle every other course by operating the end stop spindles only half as often as the comb spindles. The lines of lace openings 56 are thereby also kept parallel to the selvages and closed selvages are formed, both considered desirable features. When the heel parts 42 have been widened to the desired degree, they are then narrowed. In the form of heel shown in Figs. 1 and 2, the narrowing is performed in a single course, preferably the next one after the last lace openings in the lines 56. After said single course has been knitted, the knitting is interrupted while a considerable number of single needle narrowing operations are performed on the fabric, forming lines of fashion marks 58 in a given course. To so interrupt the knitting and to form the lines 58, a series of buttons 57 is arranged on the patterning means, including a known form of chain 59, so that the cam shaft 72 will be shogged to cause a series of fashioning cycles to be performed in succession, all in the given course in which it is desired to make lines of fashioning marks, to make a very substantial reduction in the width of the fabric at the given course, the apparatus being set at this time so that the single needle narrowing means is in operation and the pull-back pawl hereinbefore referred to intersperses idle two needle widening movements between single needle narrowing movements of the narrowing combs. The means for determining the time the pull-back pawl operates and causes a two needle outward or widening movement during each narrowing cycle will be described in detail hereinafter. Some of the buttons 55 governing the formation of lace or widening marks 56 are also shown in Fig. 14A.

In making the lines 58, the fashioning points are moved inward one needle in loop transferring movements and then immediately moved outward two needles in an idle or non-transferring

operation, cycles of single needle loop transferring inward movements and two needle idle outward movements of the combs being repeated as often as necessary to obtain the amount of narrowing desired at end of the heels. It should be observed that in the forming of the narrowed fashioning marks 58, the point combs are initially started at the further inward point and then worked outwardly in the manner herein prescribed.

10 The fashion marks in lines 58 being formed by single needle narrowing movements, it has been found desirable that the fashion marks in lines 32 and 36 also be formed by single needle movements, whereas the fashion marks in the lines 15 46 and 50 can be formed by the more usual two needle narrowing movements. Therefore, the machine employed is desirably of a type adapted to carry out both single needle and two needle

20 narrowing and it is set to make all single needle narrowings from the beginning of the blank at the welt to the end of the heels and is then reset to make all two needle narrowings as far as the end of the toe.

25 The end stops are moved in two needles in alternate narrowing operations while forming lines 58 so that the end stops substantially keep pace with the inward movement of the edge loops of the course throughout. After lines of fashion marks 58 have been formed, one or more courses are knitted and the end stops then manually racked in to points corresponding to the selvage edges of the parts 44. At the same time that the 30 end stops are manually racked in, two additional yarn carriers are brought into operation to lay yarn to form two groups of ravel courses 60 outside the main selvages and covering the needles which would otherwise press off their loops for 35 lack of yarn.

40 After the blank 30 has been pressed off the needles at the end of courses 52, the loops of the last course of the heel parts are placed on the points of a looper, the ravel courses removed in the usual manner and the ends of the heels 45 looped together. The last toe course having also been looped, a stocking is formed from the fashioned blank 30 in the usual way by connecting its edges by a longitudinal seam, running from the toe to the heel loopings and from the heel loopings to the top of the welt, the resulting seam lying at the back of the stocking. The resulting stocking has been found to fit well and to be capable of manufacture at a high rate of 50 speed by a mechanism involving only such differences from a known mechanism as can be 55 incorporated therein without making extensive changes in the original parts.

56 Referring to Figs. 3 to 17 inclusive more in detail, 70 is a transverse frame member of a multi-section full-fashioned single-unit knitting machine in general of the well known "Reading" type. A main cam shaft 72 of said machine is journaled in a framework of which said member 60 70 forms a part and has fixed thereon various cams for actuating the knitting elements such as the needle bars, the sinkers and dividers as well as means for controlling them in making knitted fabric. A fashioning means or narrowing head, the left end of machine being shown, is also operated by cam shaft 72, the majority of the elements of said narrowing head within the invention appearing in Figs. 3 and 4. Patterning means, controlling the action of various 65 means forming parts of the machine including 70

the fashioning means, also receives its actuating impulse from shaft 72.

The fashioning means shown includes a comb spindle 74 having a screw threaded portion 75 appearing in Fig. 5 and a nut 76 on said portion 75 whereby, when spindle 74 is turned, the spindle moves the nut along the axis of the spindle, so that an arm 77 projecting upwardly from the nut correspondingly moves a narrowing rod 78 on which is fixed a comb, not shown, holding a plurality of narrowing or fashioning points. It is understood that only one nut 76 and one narrowing rod of the usual mechanism is shown in order to illustrate and describe the present invention. Said rod is mounted for longitudinal and dipping movements relative to the needles of the machine. The loops are picked off the needles by the points when they are dipped and, when the rod 78 is shifted by movement of spindle 74 and nut 76, and the points dipped again, the loops are placed on needles other than the ones from which they were lifted. This is a fashioning operation but as most such operations involve transferring the loops in the narrowing direction, the part of the machine on which the rod 78 is mounted is commonly known as the narrowing machine. As the form and operation of the narrowing machine are well known and do not need to be altered in order to cooperate with the novel features disclosed, the narrowing machine has not been shown herein.

The narrowing head as shown also includes another threaded spindle, indicated at 80 (Fig. 6), whose function it is to move end stops 81, which determine the throw of yarn carrier rods (not shown) and which are mounted on a nut 79 on the threaded portion of spindle 80 so as to be moved longitudinally of the axis of the spindle when the spindle is turned.

The spindles 74 and 80 are turned in the direction to narrow the fabric by pawls 82 and 84 respectively, best shown perhaps in Figs. 4, 12 and 13, which are pivoted at the outer ends of levers 86 and 88 journaled respectively on the spindles 74 and 80. Said pawls are biased (by the usual means, not shown) toward ratchet wheels 90 and 92, respectively, fixed on the spindles so that, unless the pawls are prevented from functioning, the spindles are turned each time the pawls are raised from the positions shown in Figs. 4, 12 and 13. The spindles 74 and 80 are turned in the direction to widen the fabric by pawls 94 and 96 respectively. Pawls 94 and 96 are pivotally mounted on an actuator 98 and are biased toward ratchet wheels 100 and 102 respectively so that, unless the pawls are withheld from operating, the spindles 74 and 80 are turned each time pawls 94 and 96 are raised from the levels at which they are shown in Figs. 3 and 4. In order that said pawls 82 and 84 may be raised to turn the spindles, levers 86 and 88 are pivoted (not shown) to the actuator 98 which is reciprocated vertically at desired times. The widening pawls, on the contrary, are shown as pivoted directly to a part fixed on the actuator 98. Pawls 94 and 96, like 82 and 84, unless prevented from operating would turn their spindles each two needles at each operation, but pawl 94 is always controlled, by means to be described, so that it never gives the spindle 74 a movement greater than a single needle per cycle. The left end of the machine being the one shown in the drawings, the spindles 74 and 80 turn clockwise

in narrowing operations and counterclockwise in widening operations.

For reciprocating actuator 98 to cause the spindles to be turned properly by their narrowing and widening pawls, the actuator has a downwardly extending arm 99 which rests between strokes of the actuator on a bolt 106 fixed to the transverse frame member 70. Pivotedly connected to arm 99 near its lower end at 109, is the rear end of a lever 108, the forward end of which is pivoted to the transverse frame member 70 at 110. Intermediate its ends, lever 108 carries an axle 111 on which is journaled a roller type cam follower 112. During knitting cycles of the machine and cam shaft 72, the plane of follower 112 lies between that of a cam 114 fixed on shaft 72 and that of a cam 116 also fixed on the shaft so that the two cams can turn with the shaft without affecting the roller. As is well understood, the cam shaft 72 is shogged or shifted to the right when viewed from the front of the machine, as in Fig. 14, at the beginning of each cycle in which the points in the combs are used for fashioning. If the follower 112 is not shifted on its axle at the time the cam shaft shifts, cam 114 is brought into the plane of the follower and the cam acts to raise actuator 98 and thereby the pawls pivoted thereon or thereto. Either the narrowing pawls or the widening pawls are permitted to act when the actuator is operated by cam 114 but only the widening pawls when the actuator is moved by cam 116. So long as the fashioning points in the combs are to act on the loops, follower 112 is held fast in the plane in which it is shown in Figs. 14 and 16 by an off-set portion (not shown) which lies in a groove 115 in the hub of the follower, off-set portion being integral with a plate 117 which is shown in dotted outline in Fig. 16 and which is removably fastened to the underside of lever 108 by a screw 119. If it is desired to operate spindles 74 and 80 during knitting revolutions, in which the cam shaft 72 is not shogged, plate 117 is removed from lever 108 and follower 112 is shifted on its axle in the same direction that the shaft 72 shifts when it is shogged for carrying out a fashioning cycle so that the follower 112 moves into the plane of the cam 116 and actuator 98 is raised by this cam, the shifting of follower 112 being caused by means described hereinbelow.

For controlling the narrowing pawls and the widening pawls to act with the cam 114 or 116 respectively as desired, means are provided including plate cams 118 and 120 on spindles 74 and 80 respectively, said plate cams mounted to turn on the spindles near the ends of the latter in planes at right angles to the axes of the spindles. Cams 118 and 120 are connected by a link 122 the ends of which are pivoted to the cams so that the two cams must swing together when they are moved around the spindles. Cams 118 and 120 are so formed and the length of link 122 so adjusted that, when the cams are swung clockwise as viewed in Fig. 4, the camming edge of cam 120 contacts a roller 124 on pawl 84 to hold the pawl in a position preventing it from engaging its ratchet wheel. At the same time pawl 82 is similarly disabled by a connection with pawl 84 furnished by a link 126 shown in Figs. 4, 12 and 13 and which is pivotally connected to both the narrowing pawls, conveniently as shown at points below their pivots. Pawls 82 or 84 may be moved together away from the ratchet wheels 90 and 92 respectively, by means of the link 126 or the pawl 82 may be moved away from its ratchet 90 with-

out affecting the action of the pawl 84, due to a lost motion connection, not shown, between pawl 82 and link 126, as hereinafter set forth. When the cam 120 is in position to render inoperative the narrowing pawls 82 and 84, the widening pawl 96 is free to act on its ratchet 102 as far as cam 120 is concerned, to give ratchet 102 a two needle movement. Cam 118, however, is so formed that it contacts a pin 128 on pawl 94 and limits pawl 94 to a one needle movement of its ratchet 100 even when cam 118 has been turned clockwise so as to stand in the position shown in Fig. 4.

A means for turning plate cams 118 and 120 on spindles 74 and 80 is provided which includes a link 130 connected to cam 120 through a universal joint 132 including a pivot 134 fixed to the cam as shown in Figs. 3, 4 and 7. Said turning means is so biased that link 130 stands in its lower position except during cycles involving widening movements of spindles 74 and 80, the position of the parts resulting when link 130 is so lowered being shown in Fig. 3 in which the narrowing pawl 84 is free of cam 120 and both pawls 82 and 84 can act on their ratchets, at least so far as cam 120 is concerned, these positions being retained from the beginning of the welt to the beginning of the heel in stocking 30. However, as already mentioned, it is desired that the narrowings by which lines of fashion marks 32 and 36 are made shall be single needle ones.

For this purpose, a means is provided including a cam member or cam 136 best shown in Figs. 12 and 13. Cam 136 is pivotally mounted on spindle 74 and biased by a spring 138 toward the position shown in Fig. 13 in which a corner 140 of cam member 136 prevents the narrowing pawl 82 from engaging the tooth of its ratchet 90 nearest to it when the pawl begins an upward movement from its lowest position, in which it is shown in Fig. 13. The ratchet wheel 90 therefore is turned only a one needle distance under these conditions, but operates at each operation of the actuator 98. However, the ratchet 92 for the end stop spindle 80 has teeth of twice the length of those on ratchet 90. Therefore, when the actuator 98 rises and the pawl 84 starts from the position shown in Fig. 13, it immediately engages the nearest tooth of ratchet 92 and turns spindle 80 a two needle distance. In order, therefore, that the selvages shall be uniformly closed and shall remain parallel to the lines of single needle fashion marks, means is provided whereby the pawl 84 is partially disabled in the sense that it is prevented from acting on ratchet 92 at every other reciprocation of actuator 98. For this purpose, a lever 142 is journaled on a shaft 144 carried in the frame of the machine. At its lower end, lever 142 has journaled thereon a cam follower 146 and the lever is biased so that its follower, so long as permitted, contacts the surface of a star cam 148 which is racked by a pawl and ratchet arrangement 150 (Fig. 4) at each reciprocation of actuator 98. When follower 146 is on a high point of cam 148, pawl 84 is free to turn spindle 80 by engaging a tooth of ratchet 92 as will be clear from Figs. 12 and 13 but when follower 146 is on a low point of cam 148, lever 142 is turned by a spring 152 so that the upper end of lever 142 presses a lug 154 on pawl 84 to throw the pawl away from its ratchet wheel and spindle 80 is thereby maintained idle until another reciprocation of the actuator causes a high point of cam 148 to act on follower 146, whereupon, cam 120 permitting, another two needle

movement of spindle 80 occurs. Pawl 82 has, in the meantime, given spindle 74 a single needle narrowing movement in response to each of the reciprocations of the actuator. Due to the shape of lever 142 contacting lug 154 on pawl 84 and the lost motion connection between the link 126 and pawl 82, the lever will not interfere with the pawl 82 in engaging the second tooth of ratchet 90, of its normal two needle movement, to turn the spindle 74 a one needle distance.

When the fabric has been knitted to the instep line and widening is to be performed, and, as explained above, the widening movements of spindle 74 being always only single needle and the widening movements of spindle 80 being always two needle, it is required that the widening pawl 96 be inoperative during alternate reciprocations. For the purpose, just recited, there is employed a lever 156, shown in Figs. 3 and 4, pivoted between its ends on the same axis as lever 142 and having at its lower end a cam follower 158 adapted to contact the cam 148, a spring 160 connected to the lower end of lever 156 being utilized to effect normal engagement 20 of the follower 158 and cam 148. Followers 146 and 158 are so arranged with relation to cam 148 that the follower 146 is on a high point of the cam 148 when follower 158 is on a low point of such cam, this relation being shown in Fig. 25 30. When follower 158 is on a high point of cam 148, lever 156 is held to the left of its position as shown in Fig. 4 and pawl 96 is free to act on ratchet 102 to turn the end stop spindle in the widening direction a two needle distance. When 35 follower 158 is on a low point of cam 148, lever 156 is held in the position shown in Fig. 4 and in which pawl 96 is prevented from acting during one reciprocation of the actuator 98 and a corresponding single needle movement of spindle 40 74 due to widening pawl 94. The levers 142 and 156 are therefore prevented from interfering with each other. By the action of lever 156, pawl 96 turns end stop spindle 80 a two needle distance only every other single needle movement of spindle 45 74 caused by widening pawl 94.

As is clear from Fig. 6, plate cam 120 lies in a plane behind the plane of movement of lever 142 so that the roller 124 can be made short enough to permit lever 142 to pass in front of it when the 50 lever moves to contact lug 154.

In addition to the pawls already mentioned, a pawl 162 is shown pivotally supported on actuator 98 and adapted to act as a pull-back pawl; that is to say, when it is desired to give the comb 55 spindle an idle movement in the widening direction after a narrowing movement, the pawl 162 is employed. In the stocking blank shown in Figs. 1 and 2, pawl 162 is used only in making the lines of fashion marks 58 at the lower ends 60 of the heel parts. However, this invention is not limited to using the pawl 162 to make lines of fashion marks in single courses or to using it only in narrowing operations. Pawl 162 which is designed to act upon the downstroke of the actuator and on the widening ratchet wheel 100 of comb spindle 74 is mounted, as shown, on the opposite side of spindle 74 from pawl 94, pawls 94 and 162 being connected by a spring 164 which biases them both toward the ratchet wheel 100. Pawl 162 is so proportioned that it gives spindle 65 74 a two needle stroke at each downward movement of actuator 98 provided the pawl is free at the time to act on the ratchet 100. As shown in Figs. 3 and 4 of the drawings, pawl 162 may be 70 prevented from acting on the ratchet 100 at any

11

time desired by a pin 166 which is mounted on a throw-over lever 168 (Figs. 10 and 11) pivoted at 170 on a bracket member 172 having a collar portion fixed to the link 122 and having horizontal surfaces on each side of pivot 170 a little longer than the lever 168, so that pin 166 rests on member 172 and at about the same level whether it is thrown over toward the spindle 80, and to the left of its pivot, as it stands in Figs. 3, 4 and 7 or toward spindle 74, to the right of its pivot, as it stands in Figs. 8 and 9. In either position, pin 166 is held down against an upper edge of member 172 by a throw-over spring 174 which is fixed at one end to pin 166 and at its other end to a point on member 172 directly below pivot 170. The pin 166 projects from lever 168 at both ends so that it can be used as a handle at one end to throw over the arm 168 from one position to the other and extends into the plane of pawl 162 so that it contacts the pawl when pin 166 is in its position nearer the stop spindle 80, its left position as viewed in Fig. 4, to disable the pawl by holding it away from its ratchet 100 during widening, as shown in Fig. 4, and during narrowing as shown in Fig. 7. Pin 166, however, does not hinder the operation of pawl 162 when the pin is in its position as shown in Fig. 8 whichever position the cams 118 and 120 are in. In this connection, it will be seen that, when making lines 58 in a blank such as 30, the link 122 and pin 166 stand normally in the positions shown in Fig. 8 and that, when the pin is in this position and an operation occurs to cause the pawls 82 and 84 to turn the spindle 74 and 80 in the narrowing direction, the pin 166 permits the pawl 162 to fall into engagement with its ratchet to turn comb spindle 74 a two needle distance on the downstroke of the actuator. The arm 168 is moved from its active position, shown in Fig. 7, to its inactive position, shown in Fig. 8, at the end of lines 56 of lace openings and is again returned to its position, shown in Fig. 7, at the completion of lines 58 of fashion marks.

These are the only times the pawl 162 is manipulated in making the blank 30 on the machine shown in Figs. 3 to 17, inclusive. It is desirable to set the pattern chain to stop the machine at the end of lines 56 so that the arm may be moved to its inactive position. Further, at the ends of lines 58, the machine is again stopped to reset the end stop and comb spindles to form the part 44 of the stocking at which time the arm 168 is again returned to active position to hold the pawl 162 away from the ratchet wheel 100.

As previously mentioned, the cam 136 is biased to a position in which it limits spindle 74 to single needle narrowing movements. However, it is desired to turn spindle 74 at times two needles per narrowing movement to form the narrowings 46 and 50 in the blank 30, Fig. 1. To this end, a bell crank lever 176 is provided pivotally mounted on a stud 175 carried in the frame 70 and having a vertical arm 177 and a horizontal arm 179. As best shown in Figs. 12 and 13, the upper end of the vertical arm 177 of lever 176 carries a member 181 which is adapted to engage a shoulder 178 of cam 136. The weight of the horizontal arm 179 of lever 176 biases it to the position shown in Fig. 13 in which the member 181 has no effect on cam 136 and the cam is therefore held by its spring 138 in a position in which the cam limits narrowing pawl 82 to turning spindle 74 single needle distances. In this position, a pin or lug 180 on the upper

12

branch of a loop at the free end of the horizontal arm 179 of the bell-crank lever 176 rests on a low point of a cam portion 182 of a hand wheel 184 which is pivotally carried on the shaft 144. If the hand wheel 184 is turned from its position shown in Fig. 13, in which position the pawl 82 is limited to single needle turning movements of the spindle 74, to the position shown in Fig. 12, in which the lug 180 engages a high point of cam portion 182, the lever 176 is turned to move the corner 140 of cam member 136 out of the path of movement of the pawl 82. In this position the pawl 82 moves the ratchet 90 two teeth and therefore the spindle 74 two needles per upstroke of the actuator 98.

At the same time that cam 182 turns lever 176 to move cam 136 out of the path of pawl 82, it raises a lug 186 on the loop at the free end of the horizontal arm 179 of lever 176 into engagement with a contact piece 188 which is adjustably mounted in a lug rigid with and projecting from the lever 142 to hold lever 142 in the position shown in Fig. 12 in which the lever is spaced from the pin or lug 154 and therefore cannot affect the narrowing pawl 84 which makes an effective stroke of two needles at each upstroke of actuator 98. As is clear from Fig. 12, the position of lever 142 when held by lug 186 is the same in which the lever is held by a high point on cam 148.

After the toe of the blank has been cast off, the handwheel 184 is turned to move cam portion 182 into the position shown in Fig. 13 for the next blank.

The link 130, by which the plate cams 118 and 120 are turned on spindles 74 and 80 to control the pawls 82, 84, 94 and 96 to cause them to turn spindles 74 and 80 in the desired directions when the actuator 98 is to be reciprocated, extends downward as shown in Figs. 3 and 14 and at its lower end link 130 is connected to the free end of a horizontal arm of a bell-crank lever 190, shown in Fig. 14, by means of a second universal joint 192. Bell-crank lever 190 has an arm 193 (Fig. 15) which is pivotally connected by a link 194 to a coupling member 196 fixed to a rod 198 at the rear of the machine. As is evident from the drawing, the position of rod 198 determines the position of link 130 and therefore of plate cams 118 and 120. Except when widening is to be performed, rod 198 is in its right hand position as viewed in Figs. 14 and 16 and the link 130 in its lower position in which the widening pawls 94 and 96 are held in an ineffective position and the narrowing pawls 82 and 84, so far as plate cams 118 and 120 are concerned, are free to turn spindles 74 and 80. Except during widening cycles of the machine, rod 198 is held in the position shown in Figs. 14 and 16 by means including a spring 199 which biases a collar 204, to the right as viewed in Fig. 16, into engagement with one arm 202 of a bell-crank lever 200, Fig. 15. Bell-crank lever 200 also has an arm 206 which is connected by link 208 and universal joints at each end thereof to the rear end of a lever 210 pivoted on a shaft 212 (Fig. 17) carried in a bracket 211 on the machine frame. Except in widening cycles, the front end of lever 210 is held elevated against the tension of a spring 214 by an arm 216 which is pivoted on the frame and normally held beneath the forward end of lever 210 by a rod 218 (Fig. 14) controlled by a patterning means, shown in Fig. 14a. A high point on a cam 220 on shaft 72 contacts a roller type follower 222, journaled on lever 210, at each

revolution of shaft 72 to relieve the arm 216 of the pressure of the lever 210 caused by spring 214. Except when arm 216 is moved by rod 218, however, as soon as the high point of cam 220 moves out from under follower 222, the front end of lever 210 settles back on arm 216 without result. When, however, the fabric is to be widened, as cam 220 relieves the arm 216 of the pressure of the lever 210, the pattern means moves rod 218 to swing arm 216 out from under the lever 210 and, immediately thereafter, as the follower 222 moves down onto the low portion of cam 220 under the influence of spring 214, the rear end of lever 210 is raised and with it arm 206 of bell crank lever 200 whereby the arm 202 of lever 200 is moved so as to move rod 198 to the left as viewed in Figs. 15 and 16. The link 130 is thereby raised to swing plate cams 118 and 120 clockwise as viewed in Figs. 3 and 7, the movement of link 130 being imparted directly to cam 120 and from cam 120 to cam 118 through the link 122. The narrowing pawls are thereby prevented from acting and the widening pawls permitted to act to move the spindles as the actuator 98 is raised except when pawl 96 is held away from its ratchet by lever 156. When again the high point of cam 220 passes underneath roller 222, the arm 216 is returned to the position, shown in Fig. 14, and in which it sustains lever 210, rod 198 being returned to its initial right-hand position by the spring 199 assisted by the weight of link 130.

When, however, rod 198 is shifted to the left to lift link 130, its movement may be utilized to also shift the follower 112 so that the widening cam 116 on cam shaft 72 will operate lever 108 and actuator 98 instead of the narrowing cam 114, cam 116 operating at different points in the revolution of shaft 72 than cam 114 as is clear from Fig. 3 and also during the couloring of the yarn instead of a narrowing operation of the machine. For so shifting follower 112 from rod 198, the plate 117 having been removed to permit it, a lever 224 is pivoted on the frame at 226, lever 224 having its rear end extended down between two collars 228 and 229 fixed on rod 198 near its left end so that as rod 198 moves to the left as viewed in Fig. 15 to lift link 130, the rear end of the lever 224 also moves to the left and the front end of lever 224 moves to the right. As the front end of lever 224 is forked and embraces the edge of follower 112 as shown at 230 in Fig. 16, the rightward movement of the front end of lever 224 shifts follower 112 into the plane of the widening cam 116. However, when widening by points, collar 229 is left free on rod 198 so that it exerts no pressure on lever 224 and therefore will not shift the follower 112.

Due to the timing of the action of the widening pawl 96 when the cam 116 is employed, which occurs during the couloring of the yarn, together with the positive lifting of a locking plunger 232 from an indexing dial 234 by means of a cam 233 (Fig. 6) secured to and movable with the lever 88, there is danger that the spindle 80 may over-run, particularly when the carrier rod strikes its end stop. To prevent such over-running action a stop pawl 236 is provided, for engagement with the ratchet 92, which is pivoted on a shaft 239, commonly provided in the "Reading" type full-fashioned knitting machine, and which is released at the proper time from the ratchet 92 before pawl 96 has finished its up-stroke, so that pawl 236 can drop onto a tooth of ratchet 92 to stop the spindle in the proper an-

gular position. The means by which said stop pawl 236 is lifted and released at the proper times to permit spindle 80 to be turned and then stopped includes a finger or lever 240 which is pivoted on a stud 242 on an arm 244 also fixed to and movable with the lever 88. Said finger 240, as shown, lies between arm 244 and pawl 236 and the finger has a lug or pin 237 which is held in engagement with the edge of arm 244 by a spring 238 (Fig. 6) to hold the finger rigid with the arm when the pawl 236 is to be lifted, a pin 246 adjustably fixed in pawl 236, so as to extend toward the finger 240, engaging a lateral extension 241 on finger 240 to lift the pawl as the finger rises from the position in which it is shown in Fig. 4. Pin 246 and the extension 241 of finger 240 become disengaged after the pawl 236 has been lifted to a certain height to permit the pawl to drop onto ratchet 92 to stop it at the desired time. Said pawl 236 and associated actuating means forms no part of the present invention and is not claimed herein.

The pawl 236 also has an arm 245 which is connected by a bolt 247 to a link 249. The link 251 has a slot 251 therein whereby a stem of a bolt 248 may slide in the slot to provide a lost motion connection between the link and the pawl 84. With this arrangement both pawl 84 and stop pawl 236 may function in the manner hereinbefore set forth without interfering with the operation of the other. However, when it is desired to manually reset the spindles, the pawl 84 is manually moved to the left of its position shown in Fig. 4 which action also raises the stop pawl 236 out of the path of the teeth in the ratchet 92 during such resetting movements.

A blank 250 which is also within the invention is shown in Figs. 18 and 19. Blank 250 is the same as blank 30 so far as the welt, the upper leg narrowings, the lower leg narrowings, the gusset narrowings and the toe narrowings are concerned. The same reference characters have therefore been applied to said leg, gusset and toe narrowings in Fig. 18 as in Figs. 1 and 2. Heel parts 252 are shown in Fig. 18, however, and form parts of blank 250 which are of quite different construction from heel parts 42 of blank 30.

Like heel parts 42, parts 252 have gore lines formed by lace openings 257, said lines having reference characters 254 thereon. The lines 254 have the same inclination to the walewise direction for the first part of their length as have the lines 56, the individual lace openings in both sets of lines being spaced from those next to them by single plain courses and each being caused by single needle outward movements of wide combs moving the edge loops outward to widen the fabric by one needle at each selvage and without any other fashionings in said first parts of heel parts 252, so that said first portions of lines 254, like lines 56, are parallel to the selvages. In the latter portion of heel parts 252, however, lace openings are made only every third course instead of every other course and single needle narrowings are made in every course, causing by reason of a particular routine to be presently described, the lace openings to be all in a single wale in the latter portions of the lines 254. At the course in heel parts 252 at which narrowings are first performed, the selvages change directions forming vertices 256 of angles in the selvages. The lace opening in Fig. 19 indicating lace openings in lines 254 falling in the course passing through said vertices is numbered 258. The widening cycle in the course containing lace

opening 258 and in any following course containing a lace opening is, however, followed by a narrowing cycle making fashioning marks 260 in the same course. In making the blank shown in Figs. 18 and 19, the combs are stepped out two needles immediately after the completion of lace opening 258 and each of the following openings so that, at the beginning of the narrowing cycle leading to the formation of fashion marks 260, the innermost fashioning points are two needle spaces from the needles holding the innermost outwardly transferred loops. Therefore, after the narrowing cycle the loops forming fashion marks 260 are a single needle distance outside the innermost outwardly transferred loops. Immediately after the formation of the course following the one containing openings 258 and marks 260, a narrowing cycle is performed causing the formation of fashion marks 262, one wale inwardly from the wales having marks 260 therein. Immediately following the formation of fashion marks 262, another course is knitted followed immediately by a narrowing revolution to form fashion marks 262 one wale inwardly from the ones containing marks 262. It will be seen that there is a cycle of four fashioning operations performed in three immediately successive courses in heels 252 beginning with the course containing vertices 256, the first course of the three to be knitted containing both single needle lace or widening and single needle narrowing marks, so that there is no net change in position of the selvage loops in the first course of said group of three, and the next two of the three containing only fashion marks, so that the selvage loops are moved inward. It will be seen further that the fashion marks 260 in the first line of the three are shown two wales or needle spaces further from the center line of the blank than the lace openings 258 while fashion marks 262 are one needle closer to said center line than marks 260 and fashion marks 264 are one needle closer to the center line of the blank than marks 262, resulting in lines diverging somewhat from the selvages going in the direction of knitting because the line formed by a single group of three fashion marks moves toward the center lines of the blank at the rate of one needle per course and a selvage moves toward the center line of the blank only two needles in three courses. The same routine is then repeated in every group of three courses following the one containing fashion marks 264 as far as the course next to the lower ends of the heel parts. In the course following the one containing the last fashion marks in the heel parts, the end stops are manually moved inward and ravel courses 266 formed, as hereinbefore set forth in connection with blank 30.

The mechanism of the form of the invention shown in Figs. 21 to 29, inclusive, is in many respects the same as that of the form of invention shown in Figs. 3 to 17 inclusive. Therefore, wherever an element or means appearing in Figs. 21 to 29, inclusive, has the same form, function and position in the machine as a part appearing in Figs. 3 to 17, inclusive, the two elements or means either have the same reference character in both groups of figures or are not referred to in connection with the group of figures composed of Figs. 21 to 29. The operations required to make lines of fashion marks 32 and 36 and the upper parts of the lines 254 of lace openings in blank 250 are performed in the same way and by the mechanisms and elements as in mak-

ing lines 32 and 36 and the lines 56 in blank 30, lines 32 and 36 being composed of fashion marks formed by single needle narrowing operations in both blanks and the lines 56 and the upper parts of lines 254 being formed by single needle widening operations in both blanks. After lace openings 258 have been formed, however, a different routine is followed in the course containing lace openings 258 and those following it from any routine used in making blank 30 and certain modifications of the apparatus are therefore required to make blank 250 compared to that used for blank 30. In making blank 250, the innermost fashioning points must be stepped out toward the selvages two needle spaces immediately after the widening movement of the points in making lace openings 258 and the lace openings following it and at no other times, while, in making blank 30, the fashioning points are stepped out two needle spaces immediately after making each of the fashion marks in lines 58 and at no other times.

To provide for said change in routine, the form of apparatus shown in Figs. 21 to 29, inclusive, is modified as compared to that shown in Figs. 3 to 17 inclusive, as to the operation of a pawl 268 shown in Fig. 21 and parts associated therewith, the pawl operating in this instance to move the point comb spindle 74 in the widening direction after forming certain of the lace openings. The pawl 268 occupies the same position with respect to the actuator as pawl 162 shown in Figs. 3 and 4. For making the desired change in the routine, a collar member 270 on link 122 is so placed that throw-over pin 272, similar to pin 166, permits pawl 268 to act on ratchet 100 for the comb spindle after widening operations when the pin is in its left hand position as viewed in Figs. 21 and 23. Therefore, the pin 272 is kept in its left hand position throughout and, during periods when the upper parts of lines 254 are being produced and no operation of pawl 268 is desired another means of controlling the pawl is provided which, however, permits the pawl 268 to act in the period of forming the lace openings from lace openings 258 onward. Said other means for controlling pawl 268 includes a link 274 which connects the pawl with the lower end of an arm 276, the upper end of which is fixed to a shaft 278, a shaft similar to shaft 239. As best shown in Figs. 25 to 29 inclusive, arm 276 has an integral extension 280 which carries one end of a bar or rod 282 above and parallel to shaft 278. Mounted on extension 280 and rod 282 are two cam pieces 284 and 286. Slidably mounted on shaft 278 and coupled to the nut on the end stop spindle 80 by connections between arms extending from the nut and itself is a collar 288 which moves with the nut and which has an upstanding arm 290 integral therewith on which is a cam piece 292 shown in Fig. 21 and held on the arm at a level to cooperate with cam 286 so long as piece 292 overlaps cam 286 and with cam 284 so long as it is below the upper edge of cam 292. When cam 292 overlaps cams 284 and/or 286, the former being in its lower position, the rod 282 is pushed toward the spindle 80 as viewed in Figs. 21 and 23 and the shaft 278 thereby turned clockwise as viewed in the same figures. Thereby the lower end of arm 276 is moved leftward as viewed in Figs. 21 and 23 to draw the pawl 268 in the same direction and therefore away from its ratchet 100.

However, at the beginning of blank 250, arm 290 is close to part 280 and the right hand corner of arm 290, when viewed as in Fig. 25, holds the

cam 284 tilted up so the position of shaft 278 is not affected, cam 284 being pivoted on part 280 at 285 at the lower right hand corner of cam 284 to permit it to be tilted. Cam 284 also has a pin 294 fixed therein which extends above the rod 282 so that, when the narrowing operations have caused arm 290 to pass to the left of the end of cam 284, cam 284 settles down to the horizontal position shown in Fig. 27 in which its weight is on the pin. It will be understood that when the end stop nuts are manually moved apart on the spindles 80, in setting up the machine to begin a blank, the cam 284 is automatically lifted. To this end, the cam 284 has adjustably mounted thereon, by screws 295, an auxiliary cam block 296, of generally rectangular form except at its lower left hand corner as viewed in Figs. 25 to 29 which is cut off to form a cam face 298. Therefore, as collar 288 and arm 290 move rightwardly along shaft 278 from cam 286 to cam 284, the arm 290 and cam piece 292 contacts face 298 to lift the cam 284 and, as soon as the upper right hand corner of cam piece 292 passes the lower right hand corner of cam face 298, a spring 300, one end of which is connected to the arm 276 and the other end to actuator 98 (not shown), draws arm 276 counterclockwise as viewed in Fig. 21 to release pawl 268 and to move the body of cam 284 above the arm 290 so that the cam is held up out of effective position, as shown in Figs. 25 and 29. During the knitting of the welt and leg of blank 250, therefore, when arm 290 is moving to the left from the position of Fig. 25 in forming the lines of fashion marks 32 and 36 auxiliary pawl 268 is not affected by cams 284 and 286 and link 274 but the pawl 268 is nevertheless prevented from operating during the formation of lines of fashion marks 32 and 36 because the throw-over pin 272 is in its extreme leftward position as viewed in Figs. 21 and 23 and acts to hold pawl 268 away from its ratchet during the narrowing movements. Now when the nut on end stop spindle 84 has moved the left hand edge of arm 290 to a position in which it begins to overlap cam 286, cam piece 292 on arm 290, due to a bevelled edge (not shown) on cam piece 292 along its left edge and a bevel 287 on cam 286, rides upon cam 286 and moves shaft 278 clockwise as viewed in Fig. 21 and thereby holds pawl 268 in ineffective position. This action also permits cam 284 to drop into its lower position as shown in Fig. 27. Therefore when the machine begins to make the lace openings forming gore lines 254 and travelling cam piece 292 moves from left to right, cam piece 292 being in active contact with 286, auxiliary pawl 268 is maintained ineffective to shift the point comb on the downstroke of the actuator. Further, by the time cam piece 292 has been moved off of cam 286 it moves onto cam 284 because the latter cam is then horizontal as shown in Fig. 27 and pawl 268 continues to be ineffective. As arm 290 and cam piece 292 continue to move rightward along cam 284 as viewed in Figs. 27, 28 and 29, the upper right hand corner of cam 292 contacts the inclined cam surface 298 on block 296 and begins to raise the block and cam 284 as shown in Fig. 28. When the knitting of heel parts 252 has progressed to the knitted course containing lace openings 257, the one just before the course containing lace openings 258, the upper right hand corner of cam piece 292 has passed along the entire length of the cam face 298 to a point where the lower edge of block 296 is parallel to and flush with the lower edge of cam 284. At 75

this point, the corner of block 290 slides on cam 284 and shaft 278 turns counterclockwise as viewed in Figs. 21 and 23 so that arm 276 and link 274 release pawl 268 to permit it to act on its ratchet 100 during fashioning revolutions. As the cams 118 and 120, link 122 and pin 272 are in the position for widening, the pawl 268, therefore, if not otherwise prevented, would at this time act on ratchet 100 to turn spindle 74 a two needle distance on the downstroke of actuator 98 in the revolution in which lace openings 257 are made and in each subsequent widening revolution. However, for reasons to be presently given in detail, it is desired that pawl 268 shall not operate in the revolution in which lace openings 257 are made and means is shown comprising a projection 302 at the right end of link 274, a bell-crank lever 304 and a link 306 connecting lever 304 to a hold out lever 308 (Figs. 21 and 22), similar to lever 156, by which lever 304 is operated to press against extension 302. Except for its action on pawl 268 through parts 302, 304 and 306, lever 308 is the counterpart of lever 156.

In said means for determining if pawl 268 will act on spindle 74 and comprising extension 302 of link 274, the bent lever 304 is shown as having a portion 305 the free end of which is enlarged for cooperating with projection 302, as shown in Figs. 23 and 24. Lever 304 is pivoted on the same stud 175 as the lever 176, the lever 304 being connected, as hereinbefore set forth, by means of the link 306 to lever 308. As is clear from the drawing, when lever 308 swings clockwise under the influence of its spring 160 (Fig. 23), lever 304 is swung counterclockwise by link 306 and the end of horizontal portion 305 thereupon contacts the free end of extension 302 to throw pawl 268 away from its ratchet. However, when lever 308 is swung counterclockwise by star cam 148, the portion 305 is withdrawn from engagement with extension 302 and pawl 268 is free to act on the downstroke of the actuator to turn spindle 74 to move the point combs outward each a two needle distance.

From the foregoing, it will be seen that the pawl 268 will be held out of engagement with its associated ratchet wheel 100 at all times when the parts are positioned to produce narrowing operations. Further, that the pawl 268 is only permitted to engage the ratchet 100 when the parts are positioned for widening, and then only as controlled by the lever 308.

Summary of operation

The operation of each of the two forms of mechanism within the invention will be obvious to those skilled in the art from the foregoing description. For purposes of convenience, however, the operation may be summarized as follows:

When a fashioning cycle is to be performed the main cam shaft 72 is shogged to the right as viewed from the front of the machine. The narrowing heads of the machine, located one at each end, comprise two threaded spindles apiece, the end stop spindle 80 operating the stops which determine the throw of the yarn carrier or carriers and the comb spindle 74 operating the combs for moving loops from the needles on which they were formed to needles one or two needles distant therefrom. Narrowing pawls 82 and 84 respectively, are provided for the comb and end stop spindles and widening pawls 94 and 96, respectively, for the comb and end stop spindles, both sets of pawls having cooperating ratchet wheels. For turning said spindles, said pawls are

connected to the actuator 98, having an up and down movement, to act on the upstroke of the actuator. As the spindles of the narrowing heads turn sometimes in the narrowing direction and sometimes in the widening direction, control cams 118 and 120 are provided to determine which set of pawls shall act on the spindles, said cams being shown as of the plate type and pivoted on the spindles. Said plate cams lie normally in an angular position in which the widening pawls are prevented from acting on their ratchets and the narrowing pawls are free to act, this position of the parts being shown in Fig. 3. Therefore, when a widening cycle is to be performed, the said plate cams are swung on the spindles to a position such as is shown in Figs. 4 and 21 and in which the narrowing pawls are both thrown into ineffective position by plate cam 120 and widening pawl 94 is permitted by cam 118 to make a single needle effective stroke. The plate cams are shifted from one position to the other by a mechanism including the link 130 which moves up and down at times and which is moved by a mechanism thrown into action by the pattern means in fashioning revolutions before the actuator begins to move in revolutions of shaft 72 in which a widening fashioning is to be performed. The link 130 always moves down to its initial position at the end of each widening revolution and must therefore be raised at the start of each widening revolution.

The actuator 98 has sufficient movement to turn the spindles a distance equal to two needles although at least some of the movements of the comb spindle 74 are only single needle movements, the widening pawl 94 for the comb spindle being always limited to single needle effects by cam 118 and the narrowing pawl for comb spindle 74 being controlled to produce single needle effects when desired by cam 136, shown in Figs. 12 and 13. As the spindle 80, however, always makes two needle movements and it is desired to keep the combs and end stops in step, means are shown whereby spindle 80 is maintained stationary at every other single needle fashioning movement of spindle 74.

As shown, said means comprises the star cam 148 and levers 142 and 156 acting during single needle fashioning periods only, one on the narrowing pawl and one on the widening pawl for the stop spindle, to render ineffective one of the pawls only in each fashioning revolution and each pawl in alternate fashioning revolutions. Said star cam is shown as operated from the actuator 98 for operating all the pawls for the comb and stop spindles. As shown, the followers for said levers are held against the star cam by springs and the levers for disabling the pawls for the end stop spindle are effective when the followers are on low points of the star cam while the levers are held away from the pawls they control when their followers are on the high points of the cam. As shown, the pawl for the star cam and the pawls for spindles all act on the upstroke of the actuator. If the follower for one of the holding out levers is on a low point of the star cam at the end of the downstroke of the actuator, the holding out lever then holds the pawl it acts on away from its ratchet at the start of the next upstroke of the actuator and, although the pawl for turning the star cam begins to move at the same time, or nearly so, as the pawl for the spindle, the latter pawl misses the tooth of its ratchet nearest it at the time and therefore runs idly up the face

of the next tooth of the ratchet and back again without affecting the ratchet and spindle. If the cam follower for the holding out lever is, however, on a high point of the star cam at the end of a downstroke of the actuator, the lever is then away from the pawl it acts on and, at the beginning of the next upstroke of the actuator, the pawl engages the nearest tooth of its ratchet and starts to turn the stop spindle at least as soon as the pawl for the star cam engages a tooth of its ratchet and starts to turn the cam. As the pawl for the spindle is pressing against a tooth of its ratchet at the time, the spring for the hold out lever is not, for a time, able to move the pawl away from its ratchet but does so as soon as the pressure against the pawl is released so that the spindle will again remain inactive on the next stroke of the actuator. It will be noted, however, that as the follower for one hold out lever is on a low point of the star wheel cam at the same time the follower for the other hold out lever is on a high point, it is quite possible to operate the end stop spindle in immediately successive single needle fashioning cycles although in opposite directions.

In addition to the pawls used to turn the comb and stop spindles when loops are being transferred, there is a fifth or auxiliary pawl pivoted on the actuator for giving the comb spindle an idle movement of two needles on the downstroke of the actuator. In the apparatus shown in Figs. 3 to 17, said fifth pawl is designated 162 and, in the apparatus shown in Figs. 21 to 29 inclusive, the fifth pawl is designated 268. In both forms of apparatus, said fifth pawl is not used except during certain fashioning revolutions when forming the heel portions. In both forms of apparatus also, said fifth pawl is controlled at least in part by a throw-over pin which is mounted on a collar fixed on the link 122 connecting plate cams 118 and 120.

In the form of apparatus shown in Figs. 3 to 17 inclusive, however, the fifth pawl 162 is used only in narrowing revolutions and is controlled entirely by the throw-over pin. In this form of apparatus, the throw-over pin is in its left position as viewed in Figs. 3 and 4 from the start of knitting a blank until near the lower end of the heel and prevents the pawl 162 from acting to move the comb spindle in any fashioning operations until all the desired lace openings have been formed near the end of the heel parts. At this time, the position of the throw-over pin is changed from one at the left of its pivot to one at the right of its pivot and the pawl 162 then acts as a pull-back so that a series of single needle narrowing operations may be performed in a single course near the lower ends of the heel portions, resulting in lines of fashion marks 58 shown in Figs. 1 and 2. It will be seen in this connection that, as pawl 82 is adapted to turn the spindle on the upstroke of the actuator 98, it in nowise interferes with the movement of spindle 74 caused by the pawl 162 on the ensuing downstroke of the actuator. After the course in the heel containing the single needle narrowings, the throw-over pin is returned to its left hand position and the lever 176 turned clockwise as viewed in Fig. 4 so that the remaining narrowings in the blank, those under the instep and in the toe, are made of the two needle type.

When making blanks as shown in Figs. 18 and 19, however, the collar on which the throw-over pin is mounted is set in a slightly different posi-

tion on link 122 with the material difference in result that the fifth or auxiliary pawl 268 on the actuator operates to turn the ratchet 100 for comb spindle 74 during widening operations, but not during narrowing, when the throw-over pin is in its left hand position when viewed as in Figs. 21 and 23. The throw-over pin is therefore placed in its left hand position at the beginning of work on a blank in the apparatus shown in Figs. 21 to 29 inclusive and remains there until the blank is completed. In the major portions of the heel parts 252, therefore, where the selvages are widened and the gore lines 254 are parallel to the selvages, a special means is employed to prevent pawl 268 from operating to step the ratchet 100 two needles in the widening direction after the formation of each lace opening. The cam arrangement shown in Figs. 25 to 29 inclusive acts in the desired manner to hold the pawl 268 in inactive position by means including the arm 276 and link 274 until the knitting of blank 258 has reached a point two courses before the points 256 on the selvages. Here lace openings 257 are formed and arm 290 and cam 284 permit pawl 268 to work, as far as they are concerned, lever 304 then disabling pawl 268 in alternate fashioning revolutions while throw-over pin 272 disables it in all narrowing operations.

The lace openings 257 are odd numbered counting from the first lace openings in lines 254, it being understood that the lever 308 permits pawl 96 to act on its ratchet at the time the first lace opening is made and therefore at the time each odd numbered lace opening is made. Said lace opening 257 is assumed to be opening forty-one, it being understood in this connection that lines 254 are shown diagrammatically in Fig. 18 in that it has not been attempted to show all the lace openings in the lines. Therefore, as the actuator 98 starts its upstroke to make opening 257, lever 308 is at the left as viewed in Fig. 23 and pawl 96 engages a tooth of its ratchet to turn spindle 80 two needles. As soon, however, as the pawl 96 reaches the top of its path and the pressure on it is released, the spring on lever 308 snaps it over into its right hand position shown in Fig. 21 in which not only is pawl 96 held away from its ratchet but link 306 holds lever 304 in position to block pawl 268 away from ratchet 100. Therefore, although it had been released by link 274 at the time, pawl 268 does not act in the revolution resulting in lace opening 257. A plain course is next knitted and then the course is knitted in which opening 258 is to be made. A fashioning revolution is then begun in which the levers 308 and 304 act oppositely to what has just been described as regards their action when lace opening 257 is made and the pawl 268 is permitted to act on the downstroke of the actuator so that the innermost fashioning point in each comb is stepped out a distance of three needles, one needle by the widening pawl 94 to form opening 258 and an idle two needle movement by the auxiliary pawl 268. However, in this revolution, lever 308 prevents the end stop spindle from acting. Then follows a narrowing revolution to form mark 260 in the same course as lace opening 258 and in this revolution lever 142 prevents the end stop spindle from operating. Then two courses are knitted each followed immediately by a narrowing revolution forming marks 262 and 264, respectively. In the revolution in which marks 262 are made, pawl 268 would engage ratchet 100, except that the plate cams 118 and 120 are in narrowing position and

the throw-over pin 272 holds pawl 268 away from the ratchet. In this course, however, lever 142 permits pawl 84 to turn end stop spindle 80 two needles in the narrowing direction. At completion of the mark 264 the innermost fashioning point is again in the same wale from which the loop was transferred in forming opening 258. In the third course from lace opening 258, a fourth fashioning operation, resulting in another lace opening, is made and, this being an even numbered operation after the one resulting in opening 258, pawl 268 operates to initiate another cycle of three fashion marks. In this course, levers 142 and 308 prevent the end stop spindle from operating. Such cycles are repeated several times as shown in Fig. 19 to complete the heel parts 252 as far as the course next before the ravel courses 266. It will be seen that the cycle followed in the last portion of heel parts 252 is largely the result of keeping the throw-over pin in its leftward position, the result being that lever 304 is effective only once, that is in the revolution resulting in the formation of opening 257. In the formation of the opening 258 and all the remaining openings, the lever 308 moves from a low point to a high point of cam 148 whereby lever 304 is moved away from the projection 302 on link 274 to permit the pawl 268 to operate on the downstroke of the actuator 98 and idly turn the spindle 74 a two needle distance in the widening direction.

Furthermore, where it is desired that the gore lines in the heel parts of a blank are not to follow a walewise line near their lower ends, as in Figs. 18 and 19, the apparatus shown in Figs. 21 to 29 inclusive, including bell-crank lever 304 and hold-out lever 308, can be used without change to make a blank 320 a portion of which is shown in Fig. 20 similar to blank 250 except as to the lower heel portions in which the lower ends of the gore lines extend from one end to the other with only a slight angle therein and the fashion marks accompanying the lace openings in the portions of the heel parts below the vertices 256 in the selvages are arranged in triangular groups of three instead of in straight line groups of three inclined to both the walewise and coursewise directions.

In order to produce the fabric structure shown in Fig. 20 by the apparatus shown in Figs. 21 to 29 inclusive, it is necessary only to turn the throw-over pin from its left hand position shown in Fig. 21 to its right hand position just before making lace opening 257 whereby the pawl 268 is also free to act during narrowing revolutions except when prevented by lever 304 in coaction with extension 302.

When the apparatus of Figs. 21 to 29 inclusive is so set, the lever 304 acts at the time of making opening 257 in blank 320 the same as at the time of making opening 257 in blank 250 to prevent the pawl 268 from acting during the revolution. In the revolution in which opening 258 is made in blank 320, lever 304, as in blank 250 permits pawl 268 to act toward the end of the revolution in which lace opening 258 is made to step the point combs outward two needles. In the second fashioning revolution following the knitting of the course in blank 320 containing vertex 256 and lace opening 258, fashion marks 260 are formed the same as in blank 250, lever 304 acting toward the end of the revolution to prevent pawl 268 from moving the combs outward. After knitting the next course, a narrowing revolution is performed resulting in fashion

marks 262 in blank 320, the same as in blank 250. In this revolution, however, lever 308, link 306, lever 304 and extension 302 cooperate toward the end of the operation to permit pawl 268 to move the combs two needles outward. Therefore, after another course has been knitted and a narrowing operation performed thereon, fashion marks result such as the one shown at 322, which, as shown in Fig. 20, is immediately below mark 268. In the revolution in which mark 322 is made, auxiliary pawl 268 is again prevented from acting on its ratchet by lever 304. In the next course, another widening operation is performed, with the innermost point engaging the loop on the needle on which the fashion mark 322 was formed in the preceding course, resulting in lace opening 324. In and following the course containing opening 324, three fashion marks are made corresponding to marks 260, 262 and 322 and the same routine is repeated to the ends of the heel parts of blank 320. With this procedure, the lace opening following opening 258 follows substantially the same line as the opening preceding the opening 258. The throw-over pin 272 is then placed in its left hand position again and lever 176 is set to cause the pawl 82 for spindle 74 to produce two needle narrowings for completing the remainder of the blank.

Of course, the improvements specifically shown and described by which the above results are obtained can be changed and modified in various ways without departing from the invention herein disclosed and hereinafter claimed.

I claim:

1. In a fashioning mechanism for a single unit full-fashioned knitting machine operating in several sets of fashioning cycles, the combination of an end stop operating spindle, a comb operating spindle, pawls for turning said spindles in the direction to narrow the fabric, pawls to turn said spindles in the direction to widen the fabric, actuating means for said pawls, means adapted to control said pawls to cause them to effect two needle narrowing movements of both said spindles in one of said sets of fashioning cycles, and single needle narrowing movements of the comb spindle in another set of said fashioning cycles and a two needle narrowing movement of the end stop spindle in alternate cycles of said last set, said means adapted also to cause said pawls to effect single needle widening movements of the comb spindle in a further set of fashioning cycles and a two needle widening movement of the end stop spindle in alternate cycles of said last named set, and means to cause said comb operating spindle to effect single needle fashioning movements as well as two needle idling movements of the same in one or more of said sets of fashioning cycles.

2. In a fashioning mechanism for a single unit full-fashioned knitting machine, the combination of an end stop operating spindle, a comb operating spindle, pawls for turning said spindles in a direction to either narrow or widen the fabric, actuating means for said pawls, control means for said pawls operating to effect two needle movements of both said spindles, and said control means being operable to effect single needle movement of the comb spindle in successive fashioning cycles and a two needle movement of the end stop spindle in alternate steps of said fashioning cycles, said means adapted also to cause said pawls to effect single needle widening movements of the comb spindle and two needle operation of the widening pawl for the end stop spindle during alternate widening operations of the comb

spindle said means including a lever and a cam controlling the action of said lever, means operated by said cam for preventing operation of the narrowing pawl for the end stop spindle during alternate narrowing operations of the comb spindle, and means to idly move said comb spindle a distance of two needles in the widening direction immediately following certain of said comb spindle movements.

3. In a fashioning mechanism for a single unit full-fashioned knitting machine, an end stop spindle, a narrowing pawl and a widening pawl for said spindle, a comb spindle, a narrowing pawl and a widening pawl for said comb spindle, means to reciprocate said pawls a two needle distance, means controlling said pawls to cause them to turn said spindles in either the narrowing or the widening direction as desired, a cam adapted to limit the effect of the narrowing pawl for the comb spindle to a one needle movement, a lever adapted to control said cam to cause the narrowing pawl for the comb spindle to move it either one or two needles as desired, and a second lever operated in periods of single needle operation for preventing the narrowing pawl for the stop spindle from affecting the spindle in alternate fashioning revolutions, said levers engaging to hold the second lever in ineffective position while the first lever is in position for two needle fashioning.

4. In a fashioning mechanism for a single unit full-fashioned knitting machine, the combination of an end stop operating spindle, a comb operating spindle, a pair of pawls for turning said spindles in the narrowing direction when fashioning the fabric, a pair of pawls to turn said spindles in the widening direction when fashioning the fabric, an actuator having a two needle up and down motion to which said pawls are pivoted and on the upstroke of which said pawls all affect their spindles, means controlling said pawls to cause them to turn said spindles in either the narrowing or the widening direction as desired, means to control said narrowing pawls to cause them to effect two needle narrowing movements of both said spindles or single needle narrowing movements of the comb spindle in groups of successive fashioning cycles and a two needle narrowing movement of the end stop spindle in alternate ones of said successive fashioning cycles, means to control said widening pawls to cause them to effect single needle widening movements of the comb spindle in a second group of successive fashioning cycles and a two needle widening movement of the end stop spindle in alternate ones of said second group of cycles, an additional pawl pivoted on said actuator adapted, when permitted, to move the comb spindle idly two needles on a downstroke of the actuator, and a throw-over pin acting to prevent during narrowing said additional pawl from affecting the comb spindle when the pin is in one position.

5. In a fashioning mechanism for a single unit full-fashioned knitting machine having a cam shaft, the combination of an end stop operating spindle, a comb operating spindle, pawls for turning said spindles in the direction to narrow the fabric, pawls to turn said spindles in the direction to widen the fabric, actuating means for said pawls, means to cause said pawls to effect a two needle narrowing movement of both said spindles or a single needle narrowing movement of the comb spindle in successive fashioning cycles and a two needle narrowing movement of the end stop spindle in alternate ones of suc-

cessive cycles, and means to cause said comb operating spindle to effect single needle fashioning movements in a group of several fashioning cycles as well as two needle idle widening movements in the same revolutions of the cam-shaft.

6. In a narrowing mechanism for a full-fashioned knitting machine, an end stop spindle, a narrowing pawl and a widening pawl for said spindle, means to reciprocate said pawls, means controlling said pawls to cause them to turn said spindle in either the narrowing or the widening direction as desired, a comb spindle, a narrowing pawl and a widening pawl for said comb spindle also affected by said reciprocating and controlling means, and additional control means including a cam pivoted on the comb spindle adapted to limit the narrowing pawl for the comb spindle to a one needle stroke, a lever connected to said cam adapted to move said cam to cause the pawl to move the spindle either one or two needles as desired and biased to its single needle position, a star cam forming part of said controlling means, a lever operated by said star cam for throwing out of action the narrowing pawl for the end stop spindle in alternate cycles of a one needle narrowing series, and means adapted to latch said first lever in its two needle position.

7. In a full-fashioned knitting machine, the combination of an end stop spindle, a comb spindle, a narrowing pawl and a widening pawl for each of said spindles, means to reciprocate said pawls, actuating and controlling means adapted to move and to control said pawls to turn the spindles in either direction as desired, means adapted to act while the widening pawls for said spindles are out of action to cause the narrowing pawl for the comb spindle to give it one needle or two needle movements during narrowing cycles, an auxiliary pawl acting only in single needle fashioning cycles adapted when thrown into action to turn the comb spindle idly two needles in the widening direction, means controlling said end stop spindle during the period said auxiliary pawl is active comprising a star wheel cam adapted to turn when desired, a lever adapted to act on the narrowing pawl for the end stop spindle and controlled by said star wheel cam for throwing it out of action and into action in alternate fashioning cycles, and means turning said star cam during said period.

8. In a fashioning mechanism for a single unit full-fashioned knitting machine having a comb operating spindle, a pawl and operating means therefor adapted to turn said spindle a one needle distance in the narrowing direction when desired during fashioning cycles, a pull-back pawl adapted to turn said spindle a two needle distance in an idle movement in the widening direction after said single needle turn, and means adapted to cause a substantial number of said idle two needle widening movements in a given course interspersed between single needle active narrowing movements.

9. In a fashioning mechanism for a single unit full-fashioned knitting machine, the combination of an end stop operating spindle, a comb operating spindle, means for moving said spindles in the narrowing direction or the widening direction as desired, means including said spindles and combs causing one needle widening transfers of loops at the edges of the fabric in a series of successive courses, and means adapted to cause a substantial number of single needle narrowing trans-

fers of loops in a given course following said series.

10. In a fashioning mechanism for a single unit full-fashioned knitting machine, the combination of a comb operating spindle turning at times in a narrowing direction and at times in the widening direction, a pawl and operating means therefor adapted to turn said comb operating spindle either a two needle or a one needle distance in the narrowing direction when desired during fashioning cycles, and an auxiliary pawl operated at times by said means and adapted to turn said spindle a two needle distance in an idle movement in the widening direction after but in the same fashioning cycle in which the spindle was turned a one needle distance in the narrowing direction.

11. In a fashioning mechanism for a single unit full-fashioned knitting machine, the combination of an end stop operating spindle, combs, a comb operating spindle, means for moving said spindles in the narrowing direction or the widening direction as desired, means including said spindles and combs causing one needle widening transfers of loops at the edges of the fabric in a series of successive courses, and means adapted to cause in a single course more than two of single needle loop transferring movements of the combs in the narrowing direction alternating with two needle idling movements of the combs in the widening direction.

12. In a fashioning mechanism for a single unit full-fashioned knitting machine, the combination of an end stop operating spindle having a nut thereon, a comb operating spindle, a pawl and operating means therefor adapted to turn said comb operating spindle a one needle distance in the narrowing direction when desired during fashioning cycles, an auxiliary pawl adapted to give said comb operating spindle an idle turn for a two needle distance in the widening direction when desired during fashioning cycles, and an automatic means for holding said auxiliary pawl in inactive position during a certain portion of the period in which said nut on the spindle for the end stops moves in the narrowing direction and a lesser portion of the period in which said nut moves in the widening direction.

13. In a fashioning mechanism for a single unit full-fashioned knitting machine, the combination of combs, a comb operating spindle, an end stop operating spindle, a nut on said stop spindle and an arm on the nut, means turning said spindles at times in the narrowing direction and at times in the widening direction, a pawl forming part of said means adapted to turn said comb spindle when desired to move the combs a one needle distance during fashioning cycles, an auxiliary pawl actuated by said means and acting at times to turn said comb spindle a two needle distance in an idle movement in the widening direction after but in the same cycle in which said first pawl previously turned it a one needle distance, and an automatic means for holding said auxiliary pawl in inactive position at times including a fixed cam piece and a movably mounted cam piece, and a cam piece operated by said arm and cooperating at times with said cam pieces but acting when in a certain part of its path and the spindles move in the widening direction to throw said movable cam piece out of action.

14. In a fashioning mechanism for a full-fashioned knitting machine, the combination of end stops, an end stop operating spindle, means for moving said spindle in the narrowing direction or the widening direction as desired, means

for causing one needle widening transfers of loops at the edges of the fabric in a series of courses, means causing one needle outward transfers of loops in a second series of courses while maintaining the end stops stationary, means transferring the edge loops and some others one needle inwardly in the courses of said second series to restore the edge loops to their original positions, means causing one needle narrowing transfers of loops in a series of immediately successive courses including said second series, and means turning said stop spindle to move its stops inwardly two needles in courses intermediate pairs of those of said second series of courses.

15. In a fashioning mechanism for a single unit full-fashioned knitting machine, the combination of end stops, an end stop operating spindle, combs, a comb operating spindle, operating means, means for causing said means to move said comb spindle to cause one needle widening transfers of loops at the edge of the fabric in a series of courses and for moving the end stop spindle two needles in the widening direction in alternate courses of the series, means causing said operating means to move the comb spindle for causing one needle outward transfers of loops at the edge of the fabric while maintaining the end stops stationary in a second series of courses, means causing said operating means to move the comb spindle to cause one loop inward transfers of the edge loops in the courses of said second series to restore the edge loops to their original positions, means causing said operating means to move said spindles, stops and combs to cause one needle narrowing transfers in a third series of immediately successive courses including said second series, and an auxiliary pawl and means causing said operating means to move said auxiliary pawl to move the combs idly two needles outwardly immediately after the outward transfers in said second series of courses.

16. In a fashioning mechanism for a single unit full-fashioned knitting machine, the combination of a comb spindle, an end stop spindle, narrowing pawls for said spindles, widening pawls for said spindles, means to reciprocate said pawls in two needle strokes, means adapted to control said pawls to turn the spindles in either direction as desired but the comb spindle only in single needle steps when widening, means adapted to act while the widening pawls for said spindles are out of action to cause the narrowing pawl for the comb spindle to give it one needle movements during narrowing cycles, an auxiliary pawl acting when thrown into action to turn the comb spindle idly two needles in the widening direction and means acting at times to throw said auxiliary pawl into action in the same cycle in which there has been a single needle widening transfer of loops.

17. In a fashioning mechanism for a single unit full-fashioned knitting machine, the combination of a comb spindle, an end stop spindle, narrowing pawls for said spindles, widening pawls for said spindles, means to reciprocate said pawls, means adapted to control said pawls to turn the spindles in either direction as desired, means adapted to cause the narrowing pawl for the comb spindle to give it one needle movements during narrowing cycles, an auxiliary pawl biased toward a position to turn the comb spindle idly two needles in the widening direction, means restraining said auxiliary pawl from acting on the comb spindle throughout a number of consec-

utive fashioning cycles, and means acting when said restraining means is out of action to hold the auxiliary pawl out of action in alternate fashioning cycles.

5 18. In a fashioning mechanism for a full-fashioned single unit knitting machine, the combination of an end stop spindle, a comb spindle, narrowing pawls for said spindles, widening pawls for said spindles, means to reciprocate said pawls, means adapted to control said pawls to turn the spindles in either direction as desired in loop transferring movements, means adapted to act while the widening pawls for said spindles are out of action to cause the pawls for the comb spindle to give it one needle movements during a series of fashioning cycles including widening loop transferring movements of the comb spindle and narrowing loop transferring movements, and an auxiliary pawl acting during said series of cycles to move the comb spindle idly during all the widening cycles of the series and certain of the narrowing cycles of the series.

19. In a fashioning mechanism for a full-fashioned single unit knitting machine, the combination of an end stop spindle, a comb spindle, narrowing pawls for said spindles, widening pawls for said spindles, means to reciprocate said pawls, control means for said pawls causing them to turn the spindles in the widening or the narrowing direction as desired, means adapted to act during a series of fashioning cycles to cause the narrowing pawl for the comb spindle to give it one needle loop transferring movements in both the narrowing and the widening directions, 35 an auxiliary pawl adapted to act on said comb spindle during said series of cycles to move the spindle idly two needles in the widening direction and a lever for restraining said auxiliary pawl from acting but in only alternate cycles of the series.

20. In a fashioning mechanism for a single unit full-fashioned knitting machine, the combination of an end stop spindle, a comb spindle, narrowing pawls for said spindles, widening pawls for said spindles, means to reciprocate said pawls, means controlling said pawls to cause them to turn the spindles in the widening or the narrowing direction as desired, means adapted to act during a series of fashioning cycles including widening loop transferring movements of the comb spindle and narrowing loop transferring movements of the comb spindle to limit it to single needle loop transferring movements, an auxiliary pawl adapted to act on said comb spindle at times during said series of cycles to move it two needles in the widening direction, and means for controlling said auxiliary pawl during said series including a star wheel and a lever arrangement restraining the pawl 55 from acting in alternate cycles of the series and acting to restrain also the widening pawl for the end stop spindle during widening cycles of the series.

21. In a fashioning mechanism for a full-fashioned single unit machine, the combination of an end stop spindle, a comb spindle, narrowing and widening pawls for both said spindles, means to reciprocate said pawls, means controlling said pawls to turn said spindles in the narrowing direction or the widening direction as desired in loop transferring cycles, said end stop spindle always two needles when moved and said comb spindle always one needle when turned in the widening direction, means adapted 70 to cause the narrowing pawl for the comb spindle 75 to cause the narrowing pawl for the comb spindle

to give it one needle movements during a series of fashioning cycles including widening loop transferring movements of the comb spindle and narrowing loop transferring movements in the same courses as the widening movements and in two courses between each two widening movements, an auxiliary pawl adapted to move said comb spindle idly two needles in the widening direction in any fashioning cycle, means controlling said auxiliary pawl during said series of cycles to move the comb spindle idly two needles in the widening direction after all the widening movements and after every third narrowing movement, and means preventing the widening pawl of the end stop spindle from acting on its spindle in any of the widening movements.

22. In a fashioning mechanism for a full-fashioned single unit knitting machine, the combination of an end stop spindle, a comb spindle, narrowing and widening pawls for said spindles, means to reciprocate said pawls, means controlling said pawls to turn said spindles in the narrowing direction or the widening direction as desired in loop transferring cycles, said end stop spindle when actuated always moving in two needle steps and said comb spindle when actuated in the widening direction always moving in one needle steps, means adapted to cause the narrowing pawl for the comb spindle to give it one needle movements during a series of fashioning cycles including widening loop transferring movements of the comb spindle and narrowing loop transferring movements in the same course as the widening movements and in two courses between each two widening movements, an auxiliary pawl adapted to move said comb spindle idly two needles in the widening direction in any fashioning cycle, means controlling said auxiliary pawl during said series of cycles to cause it to move the comb spindle idly two needles in the widening direction after all the narrowing movements but not after any of the widening movements, and means preventing the widening pawl of the end stop spindle from acting on its spindle in any of the widening movements.

23. In a full-fashioned knitting machine, the combination of end stops, a comb spindle, an end stop spindle, pawls for turning said spindles, means to control said pawls to turn the spindles in either the widening or narrowing direction as desired, a lever adapted to throw out of action the widening pawl for the end stop spindle and a follower on the lever, a star wheel contacting said follower to actuate the lever in one direction, an auxiliary pawl adapted to give the comb spindle two-needle idling movements, a link con-

nected to said pawl, a shaft having an arm fixed thereto and the arm connected to said link, a cam movable with the end stops, a cam mounted on said shaft for rotation therewith and engaging said first cam at times to turn the shaft in the direction to render said auxiliary pawl ineffective, said second cam being pivoted and having a part fixed thereto engaged by said first cam as the first cam moves in the widening direction to turn said second cam into an ineffective position and to thereby release said link and auxiliary pawl for action on the comb spindle, a lever pivoted intermediate its ends and having one end adapted to contact said link to prevent the auxiliary pawl from acting on the comb spindle, and a link connecting said first lever with said second lever and causing said second lever to hold the auxiliary pawl out of action when said first lever holds the widening pawl for the end stop spindle out of action.

24. In a full-fashioned knitting machine having movable end stop controlling means comprising a cam movable with the end stops, and a cam piece mounted to turn about an axis parallel to the path of said cam and pivoted on an axis generally at right angles to the vertical plane through the path of said cam, said cam piece acting in conjunction with said cam so as to be turned about said first axis when said cam is moving in one direction, whereby the cam piece is adapted to produce a motivating effect, the cam piece having an inclined portion contacting with a corner of said cam as the cam moves in the other direction to throw the cam piece into an inactive position.
